UNITED STATES PATENT OFFICE.

PAUL J. BARORD, OF DORMONT BOROUGH, PENNSYLVANIA.

METHOD OF AND APPARATUS FOR COATING.

Application filed August 27, 1926. Serial No. 131,892.

This invention relates to a method and apparatus for coating the surface of objects with liquid or fluid coating materials and, while not limited thereto, the present embodiment of the invention relates more specifically to the coating of pipes or other cylindrical objects with a fluid coating material such as paint.

5

One object of this invention is to provide 10 a method and apparatus which will be entirely automatic in operation.

Another object is to provide a method and apparatus which will form a uniform and even coating over the entire object or surface 15 being coated.

A further object is to provide a method and apparatus in which none of the coating material will be wasted.

A still further object is to provide a 20 method and apparatus having the novel features described in the following specification and illustrated in the accompanying drawings.

In the drawings—

25 Figure 1 is a side elevation of a machine for carrying out the method of this invention.

Figure 2 is an end elevation thereof.

Figure 3 is a longitudinal sectional elevation.

30 Figure 4 is a front elevation of one of the nozzles.

Figure 5 is a sectional view on the line V—V of Figure 4.

35 Figure 6 is a fragmentary detail sectional view on the line VI—VI of Figure 4.

In carrying out the method of this invention, an excess of coating material is first 40 flowed onto the article or surface to be coated and the surface thus coated is then subjected to a wiping action, which in the apparatus disclosed herein is performed by an air wipe, and this wiping action removes all excess coating material and forces said material 45 into the pores and interstices of the object being coated and results in the forming of a coating of uniform thickness over the entire surface of the object being coated.

The apparatus to be described is specifically 50 adapted for coating pipe, and comprises a pair of end stands 2 and 3 mounted on foundation walls 4 which are spaced to provide a space 5 in which a storage tank 6, adapted to contain a supply of coating material, is mounted.

A coating chamber forming the body of

the machine, and consisting of a hollow casting 7 is mounted between and supported on lugs 8 on the stands 2 and 3 and secured in position by bolts 9.

60 The casting 7 is provided with a settling basin or chamber 10 at its lower end, which is formed integral therewith. A pair of end walls 12 extend upwardly from the ends of the basin or chamber 10 in spaced relation 65 to the end walls of the casting forming overflow chambers 13 for receiving the coating material overflowing from the settling chamber 10.

A pair of branch drain pipes 14 lead from 70 the overflow chambers 13 to a main drain pipe 15, which pipe extends downwardly to the tank 6.

A gage 16 is provided for noting the level 75 of liquid in the settling basin 10.

A grate or open support 18 extends longitudinally or from end to end of the chamber or casting 7 above the settling basin 10 and overflow chambers 13. Filter screens 19 are supported on the grate or support 18 and 80 the walls 12 above each of the chambers 13 and cover plates 20 are hingedly supported on the grate 18 and arranged to normally overlie the chambers 13 so as to cause any liquid or coating material descending in the 85 coating chamber to flow into the basin 10, from which it may overflow into the chambers 13 through the screens 19.

A pair of baffle plates 21 are supported in spaced relation on the support 18 and extend 90 upwardly to the top of the coating chamber so as to prevent any great quantity of the coating liquid, which is applied at one end of the coating chamber and the excess of which is removed at the other end of the 95 chamber, from entering the space 22 between the plates, from which space a vent or air outlet opens into an exhaust head 23.

The exhaust head 23 is provided with baffle cones 24 to baffle the air escaping from 100 the coating chamber and remove any coating material entrained therein. Any coating material trapped by the cones 24 will drain through the conduit 25 and pipe 26 back into the coating chamber.

The top of the coating chamber at each side of the exhaust head 23 is closed by hinged closures 27.

The end walls of the coating chamber are provided with openings 28 through which 110 the work or object to be coated passes. The baffle plates 21 are also provided with similar

- openings 29. The openings 28 and 29 are of sufficient size to permit the largest size object or work-piece to pass, which in the present embodiment of the invention is a six inch diameter pipe.
- The openings 28 form a nozzle seat in which are seated the nozzles 31 and 32 which are locked in position by set screws 33 mounted in openings in the end stands 2 and 3.
10. Different size nozzles are used for the different diameters of pipe. However the bases of all the nozzles are of the same size so as to fit the openings 28.
- The nozzle 31 is adapted to coat the pipe 15 or work-piece and, therefore, coating material is drawn from the tank 6 through a pipe 35 by a pump 36 and forced through a pipe 37 and cored conduits 38 in the end wall of the casting 7 into the nozzle 31.
20. The nozzle 32 is adapted to direct a stream of air under pressure onto the coated pipe to remove or wipe off all excess coating material and, therefore, a pair of cored conduits 39 are provided in the end wall of the casting 25 7 and communicate with the nozzle. The conduits 39 communicate at their upper ends with an air supply pipe 40 leading from a suitable source of air supply and provided with a control valve 41.
30. A motor 42 is mounted on a base 43 mounted on one of the foundation walls 4 and has its armature shaft 44 provided with a pinion 45 which meshes with a gear 46 on a shaft 47 journaled in the end stand 2. The shaft 47 is provided with a geared connection 48 to the pump 36.
- A shaft 49 is journaled in bearings 50 on the end stand 2 and has a feed roller 51 thereon. A shaft 52 is journaled in bearings 40 53 on the end stand 3 and has a feed roller 54 thereon. The shafts 47, 49 and 52 are all provided with sprockets 55 which are connected by a drive chain 56 so as to drive the rollers 51 and 54 to feed the pipe or other work-piece through the coating chamber.
45. A pair of supporting rods 58 are mounted along each side of the casting 7 adjacent its top edge and project beyond the ends of the casting. Shafts 59 and 60 are journaled in said rods adjacent their respective ends. Vertical levers 61 and 62 are secured to the shafts 59 and 60, respectively, and connected by a connecting rod 63, and horizontal levers 64 and 65 are secured to the shafts 59 and 60 and have rollers 66 and 67, respectively, journaled thereon and extending into the path of the pipe passing through the machine.
50. A link 68 is connected to the lever 65 and to a counter-weighted operating lever 69 of the air control valve 41, so that when a pipe passes under the roller 66 it will raise the lever 64 and rock the shaft 59 and lever 61 which in turn will rock shaft 60 and levers 65 and 62 through the connecting rod 63 so as to raise the link 68 and open the valve 41 to admit air to the nozzle 32. As the pipe passes out of the coating chamber it will engage the roller 67 and thus hold the valve 41 open until after the pipe is entirely out of the coating chamber, when the valve will automatically close.
- The nozzles 31 and 32 are identical in construction and the bases of such nozzles are of the same size regardless of the size of the opening for the passage of the pipe so as to permit an interchange of nozzles.
- The cored conduits 38 and 39 in each end of the casting 7 are identically spaced so that they may be connected to either the air or coating supply as desired; therefore changing the coating and wiping ends of the machine about as desired to suit the mill layouts in which the machine is placed.
- The nozzles 31 and 32 comprise a body portion 70 which is shaped to fit within the openings 28 and are provided with bosses 71 having openings 72 therein and adapted to connect with the cored conduits 38 and 39 in the end walls of the casting 7. The openings 72 communicate with a distributing channel or manifold chamber 73. The body portion 70 is provided with a recess 74, the forward wall 75 of which is inclined forwardly and inwardly on an angle of slightly more than 45 degrees and extends from the forward edge of the manifold chamber 73 to a work-opening 76.
- A hollow nozzle plug or sleeve 77 is threaded into the recess 74 of the body portion 70 of the nozzle and is provided with an inclined forward wall 78 which is inclined at an angle of approximately 45 degrees. The plug or sleeve 77 is adapted to be threaded into the recess 74 until its forward wall is spaced a short distance from the forward wall 75 of the body portion so as to provide a relatively narrow forwardly tapering nozzle discharge port 79 through which either liquid or gaseous fluid may be discharged against the pipe or other work-piece being passed therethrough.
- A locking ring 80 is threaded on the sleeve 77 to lock it in adjusted position.
- The sludge, scale and other foreign matter settling in the basin or chamber 10 is adapted to be removed without interfering with the operation of the machine, through an opening 82 in the side of the basin 10 which opens into a cleanout pocket 83 into which the foreign matter may be scraped and removed. The pocket 83 is normally closed by a hinged closure 84.
- In carrying out the method of this invention with the above described apparatus, the apparatus is set up in a mill and the pipe to be coated will be delivered by any suitable conveying mechanism to the machine and fed endwise therethrough. As a pipe

enters the apparatus its forward end will engage the rollers 51 and 66. The roller 51 will feed the pipe into the apparatus while the roller 66 will operate the mechanism for opening the valve 41. The motor 42 will, of course, be in operation and pump 36 will be forcing coating fluid under pressure through the coating nozzle 31. The operation of the valve 41 will open the valve and admit air under pressure to the nozzle 32, and this air will be projected onto the pipe as it passes through the nozzle still carrying an excess of coating material which has been projected or flowed thereon by the nozzle 31.

15 By projecting or flowing the coating material onto the pipe under pressure an intimate contact is had between the coating material and pipe surface so as to force the coating material into any depressions or irregularities of the surface.

The stream of air projected against the pipe by the nozzle 32 will wipe or remove all excess coating material from the pipe and also force the remaining material into the pores and interstices of the pipe surface so as to provide a finished coating of uniform thickness over the entire pipe surface.

Due to the circular passageways in the nozzles 31 and 32, through which the pipes being coated are passed, which passageways are surrounded by the nozzle discharge ports 79, the coating and wiping fluids will be discharged in a stream having a substantially circular outline so as to cause said fluids to

35 be projected in substantially equal amounts and with substantially equal force against the entire surface of the pipe, thereby subjecting the entire surface of the pipe to a substantially equal application of the coating fluid and a substantially equal wiping.

40 All the excess coating material removed or wiped from the pipe will be collected in the basin 10 and returned to the source of supply so that there is no loss of coating material.

45 The present method is superior to either spraying or brushing the coating material onto the surface to be coated, since both of such methods are wasteful of the coating material; do not provide a uniform coating, and do not force the material into the pores and interstices of the surface being coated as the present method does.

While I have described certain specific steps of my method, and a certain specific 55 embodiment of apparatus for carrying out my novel method, it will be understood that I do not wish to be limited to either the specific steps described nor to the specific embodiment of apparatus described, since 60 various modifications may be made in both the method and apparatus described in adapting my invention for use in coating other objects than pipe, such as structural shapes, plain flat surfaces, and the like.

65 It will be understood that when structural

shapes and the like are being coated the nozzles 31 and 32 will be modified to have passageways having an outline substantially the same as the cross-section of the shape being coated, and the nozzle discharge ports 70 will follow the outline of the passageways so as to cause the coating and wiping fluids to be projected in substantially equal amounts and with substantially equal force against the entire surface of the shapes, the 75 same as described above when the nozzles are provided with circular passageways and discharge ports for coating objects such as pipe having a circular cross-section.

I claim:

1. An apparatus for coating the surface of an object with paint or other fluid coating material, comprising in combination, a coating chamber, a coating nozzle at one end of said chamber, a wiping nozzle at the other 85 end of said chamber, a storage vessel for the coating material, a conduit connecting said storage vessel and said coating nozzle, means for conveying the article to be coated through said chamber and past said nozzles, 90 means for feeding the coating material from said vessel through said nozzle so as to flow an excess of coating material onto said surface to be coated, means for supplying air under pressure to said wiping nozzle, and 95 said wiping nozzle being provided with an outlet passage adapted to deliver a thin stream of air onto the coated surface to wipe all excess coating material therefrom.

2. An apparatus for coating the surface 100 of an object with paint or other fluid coating material, comprising in combination, a coating chamber, a coating nozzle at one end of said chamber, a wiping nozzle at the other end of said chamber, a storage vessel for the 105 coating material, a conduit connecting said storage vessel and said coating nozzle, means for conveying the article to be coated through said chamber and past said nozzles, means for feeding the coating material from 110 said vessel through said nozzle so as to flow an excess of coating material onto said surface to be coated, means for supplying air under pressure to said wiping nozzle, said 115 wiping nozzle being provided with an outlet passage adapted to deliver a thin stream of air onto the coating surface to wipe all excess coating material therefrom, means for collecting said excess coating material wiped from the coated surface, and means for returning said material to said storage vessel.

3. An apparatus for coating the surface 120 of an object with paint or other fluid coating material, comprising in combination, a coating chamber, a coating nozzle at one end of said chamber, a wiping nozzle at the other end of said chamber, a storage vessel for the 125 coating material, a conduit connecting said storage vessel and said coating nozzle, means for conveying the article to be coated through 130

- said chamber and past said nozzles, a pump for forcing the coating material from said vessel through said nozzle so as to flow an excess of coating material onto the surface to be coated, means for supplying air under pressure to said wiping nozzle, said wiping nozzle being provided with an outlet passage adapted to deliver a thin stream of air onto the coated surface at an angle of approximately 45 degrees to the plane of said surface to wipe all excess coating material therefrom, and means for collecting said excess coating material wiped from the coated surface.
15. 4. An apparatus for coating the surface of an object with paint or other fluid coating material, comprising in combination, a coating chamber, a coating nozzle at one end of said chamber, a wiping nozzle at the other end of said chamber, a storage vessel for the coating material, a conduit connecting said storage vessel and said coating nozzle, means for conveying the article to be coated through said chamber and past said nozzles, a pump for forcing the coating material from said vessel through said nozzle so as to flow an excess of coating material onto the surface to be coated, an air pressure main connected to said wiping nozzle to supply air under pressure to said nozzle, a valve for controlling the flow of air to said nozzle, means operable by the object being coated for operating said valve, said wiping nozzle being provided with an outlet passage adapted to deliver a thin stream of air onto the coated surface at an angle of approximately 45 degrees to the plane of said surface to wipe all excess coating material therefrom, and means for collecting said excess coating material wiped from the coated surface.
40. 5. In a pipe coating machine having means for flowing an excess of coating onto the pipe, an air wiping nozzle, said nozzle comprising a body portion having a circular recess therein, a circular opening in the front wall of said recess of less diameter than said recess, said front wall being beveled outwardly and rearwardly from said opening to said recess on an angle of approximately 45 degrees, a fluid distributing channel opening through the side wall of said recess immediately to the rear of the beveled portion of said front wall, fluid supply conduits communicating with said channel, a nozzle core threaded into said recess, said nozzle core being provided with an end wall inclined at a slightly less angle than said beveled front wall of said recess so as to form a relatively narrow inclined circular fluid discharge slot slightly tapered toward its forward or discharge end, said slot being in communication with said distributing channel and adapted to discharge fluid under pressure in a relatively thin cutting stream.
45. 6. In a pipe coating machine having means for flowing an excess of coating onto the pipe, an air wiping nozzle, said nozzle comprising a body portion having a circular recess therein, a circular opening in the front wall of said recess of less diameter than said recess, said front wall being beveled outwardly and rearwardly from said opening to said recess, a fluid distributing channel opening through the side wall of said recess immediately to the rear of the beveled portion of said front wall, fluid supply conduits communicating with said channel, a nozzle core threaded into said recess, said nozzle core being provided with an inclined end wall adapted to cooperate with said beveled wall of said recess to form a relatively narrow angularly inclined circular fluid discharge slot, said slot being in communication with said distributing channel and adapted to discharge fluid under pressure in a relatively thin cutting stream.
50. 7. In a pipe coating machine having means for flowing an excess of coating onto the pipe, an air wiping nozzle, said nozzle comprising a body portion having a circular recess therein, a circular opening in the front wall of said recess of less diameter than said recess, said front wall being beveled outwardly and rearwardly from said opening to said recess on an angle of approximately 45 degrees, a fluid distributing channel opening through the side wall of said recess immediately to the rear of the beveled portion of said front wall, fluid supply conduits communicating with said channel, a nozzle core threaded into said recess, said nozzle core being provided with an end wall inclined at a slightly less angle than said beveled front wall of said recess so as to form a relatively narrow inclined circular fluid discharge slot slightly tapered toward its forward or discharge end, said slot being in communication with said distributing channel and adapted to discharge fluid under pressure in a relatively thin cutting stream, said nozzle core being adjustable to vary the width of said discharge slot, and means for locking said nozzle core in adjusted position.
55. 8. An apparatus for coating the surface of an object with paint or other fluid coating material, comprising in combination, a coating chamber, a coating nozzle at one end of said chamber, a wiping nozzle at the other end of said chamber, a storage vessel for the coating material, a conduit connecting said storage vessel and said coating nozzle, means for conveying the article to be coated through said chamber and past said nozzles, a pump for forcing the coating material from said vessel through said nozzle so as to flow an excess of coating material onto the surface to be coated, an air pressure main connected to said wiping nozzle to supply air under pressure to said nozzle, a valve

- for controlling the flow of air to said nozzle, means operable by the object being coated for operating said valve, said wiping nozzle being provided with an outlet passage adapted to 5 deliver a thin stream of air onto the coated surface at an angle to the plane of said surface to wipe all excess coating material therefrom, and means for collecting said excess coating material wiped from the coated surface.
9. In a pipe coating machine having means for flowing an excess of coating onto the pipe, an air wiping nozzle, said nozzle comprising a body portion having a recess therein, an opening in the front wall of said recess of less size than said recess, said front wall being beveled outwardly and rearwardly from said opening to said recess, a fluid distributing channel opening through the side wall of said recess immediately to the rear of the beveled portion of said front wall, fluid supply conduits communicating with said channel, a nozzle core mounted in said recess, said nozzle core being provided with 15 an inclined end wall adapted to cooperate with said beveled wall of said recess to form a relatively narrow angularly inclined circular fluid discharge slot, said slot being in communication with said distributing channel and adapted to discharge fluid under pressure in a relatively thin cutting stream.
10. In a pipe coating machine having means for flowing an excess of coating onto the pipe, an air wiping nozzle, said nozzle comprising a body portion having a circular recess therein, a circular opening in the front wall of said recess of less diameter than said recess, said front wall being beveled outwardly and rearwardly from said opening to said recess on an angle, a fluid distributing channel opening through the side wall of said recess immediately to the rear of the beveled portion of said front wall, fluid supply conduits communicating with said channel, a nozzle core threaded into said recess, said nozzle core being provided with an end wall inclined at a slightly less angle than said beveled front wall of said recess so as to form a relatively narrow inclined circular fluid discharge slot slightly tapered toward its forward or discharge end, said slot being in communication with said distributing channel and adapted to discharge fluid under pressure in a relatively thin cutting stream.
11. In a pipe coating machine having means for flowing an excess of coating onto the pipe, an air wiping nozzle, said nozzle comprising a body portion having a circular recess therein, a circular opening in the front wall of said recess of less diameter than said recess, said front wall being beveled outwardly and rearwardly from said opening to said recess on an angle, a fluid distributing channel opening through the side wall of said recess immediately to the rear of the beveled portion of said front wall, fluid supply conduits communicating with said channel, a nozzle core threaded into said recess, said nozzle core being provided with an end wall inclined at a slightly less angle than said beveled front wall of said recess so as to form a relatively narrow inclined circular fluid discharge slot slightly tapered toward its forward or discharge end, said slot being in communication with said distributing channel and adapted to discharge fluid under pressure in a relatively thin cutting stream.
12. The method of coating pipe, which consists in projecting a circular stream of coating material against said pipe so as to flow an excess of coating material on said pipe, and then directing a circular stream of gaseous fluid under pressure against said pipe at an angle of approximately 45 degrees to the surface of the pipe to remove the excess coating material from said pipe.
13. The method of coating pipe, which consists in forming a circular stream of coating material, passing the pipe to be coated through said stream so as to coat the entire circumference of said pipe simultaneously and evenly, forming a circular stream of gaseous fluid under pressure, passing said pipe through said stream of gaseous fluid, and directing said stream of gaseous fluid against the surface of said pipe at an angle of approximately 45 degrees to the surface of said pipe to remove the excess coating material from said pipe.
14. An apparatus for coating the surface of an object with paint or other fluid coating material, comprising in combination, a coating chamber, a coating nozzle having a centrally arranged passage therethrough, a discharge port surrounding said opening through which the coating material is adapted to be discharged onto the object being coated, and means for wiping excess coating material off of the object being coated after said object passes through said coating nozzle.
15. An apparatus for coating the surface of an object with paint or other fluid coating material, comprising in combination, a coating chamber, a coating nozzle adjacent one end of said chamber and having a centrally arranged passage therethrough, a continuous discharge port surrounding said opening through which the coating material is discharged onto the object being coated, said discharge port having an outline approximately the same as the cross-section of the object being coated, and means adjacent the other end of said chamber for directing a stream of air under pressure

- onto said coated object to wipe any excess of coating material therefrom.
16. An apparatus for coating the surface of an object with paint or other fluid coating material, comprising in combination, a coating chamber, a coating nozzle at one end of said chamber, a wiping nozzle at the other end of said chamber, a storage vessel for the coating material, a conduit connecting said storage vessel and said coating nozzle, means for conveying the article to be coated through said chamber and past said nozzles, means for supplying air under pressure to said wiping nozzle, and an exhaust head for permitting the air discharged from said wiping nozzle to escape from said coating chamber.
17. An apparatus for coating the surface of an object with paint or other fluid coating material, comprising in combination, a coating chamber, a coating nozzle at one end of said chamber, a wiping nozzle at the other end of said chamber, a storage vessel for the coating material, a conduit connecting said storage vessel and said coating nozzle, means for conveying the article to be coated through said chamber and past said nozzles, means for supplying air under pressure to said wiping nozzle, an exhaust head for permitting the air discharged from said wiping nozzle to escape from said coating chamber, and means for preventing the coating material wiped from the coated object entering said exhaust head.
18. An apparatus for coating the surface of an object with paint or other fluid coating material, comprising in combination, a coating chamber, a coating nozzle at one end of said chamber, a wiping nozzle at the other end of said chamber, a storage vessel for the coating material, a conduit connecting said storage vessel and said coating nozzle, means for conveying the article to be coated through said chamber and past said nozzles, means for supplying air under pressure to said wiping nozzle, an exhaust head for permitting the air discharged from said wiping nozzle to escape from said coating chamber, means in said coating chamber for baffling the air entering said exhaust head to prevent the coating material wiped from the coated object entering said exhaust head, and other means in said exhaust head for trapping the coating material entrained in the air passing through said head.
19. The method of coating objects with fluid coating material which includes forming a stream of coating material under pressure of approximately the same outline as the cross-section of the object to be coated, passing the object to be coated centrally through said stream so as to cause said coating material to be projected in substantially equal amounts and with substantially equal force against the entire surface of said object and coat the entire surface of the object evenly, forming a stream of gaseous fluid under pressure of approximately the same outline as the cross-section of the object being coated, passing said object centrally through said stream of gaseous fluid, and directing said stream of gaseous fluid against the surface of said object at an angle of approximately 45 degrees to the surface of said article to remove the excess coating material from said article.
20. The method of coating objects with fluid coating material which includes forming a stream of coating material under pressure of approximately the same outline as the cross-section of the object to be coated, passing the object to be coated centrally through said stream so as to cause said coating material to be projected in substantially equal amounts and with substantially equal force against the entire surface of said object and coat the entire surface of the object evenly, forming a continuous stream of gaseous fluid of approximately the same outline as the cross-section of the object being coated, passing said object centrally through said stream of gaseous fluid, and directing said stream of gaseous fluid against the surface of said object at an angle to the surface of said object to remove the excess coating material from said article.
- In testimony whereof, I have hereunto signed my name.

PAUL J. BARORD.
